UNITED STATES PATENT OFFICE.

GÉDÉON MAROTTE AND HORACE DUSSAULT, OF QUEBEC, QUEBEC, CANADA, ASSIGNEES
TO THE NATIONAL DOCK & DREDGING CORPORATION LIMITED, OF QUEBEC,
CANADA.

DUMPING SCOW.

Application filed July 16, 1925 Serial No. 44,037.

The present invention pertains to a novel dumping scow of the type which discharges through the bottom.

The object of the invention is a device of this character having hinged bottom sections and a control mechanism for these sections constructed to avoid too rapid discharge. In the accomplishment of this object, the hull of the vessel is divided by partitions into a number of separate bins and a pair of hinged sections are provided in the bottom of each bin. Adjacent each bin is journaled a separate shaft, these shafts are in alinement and independently connected to their respective sections in the bins. A separate locking device, preferably a pawl and ratchet, is associated with each shaft, whereby the several bins may be permitted to discharge independently. Clutch connections are provided among the aligned shafts, so that when one shaft is reversed, all shafts will be reversed with it at the same instant to close all the bins together.

The invention is fully disclosed in the following description and in the accompanying drawings in which:

Figure 1 is a side elevation of the scow;

Figure 2 is a longitudinal vertical section thereof;

Figure 3 is a plan view;

Figure 4 is a detail section of one of the sheaves;

Figure 5 is a fragmentary plan view on a larger scale;

Figure 6 is a side elevation on one of the sheaves;

Figure 7 is an edge view thereof;

Figure 8 is a detail of the pressure cylinder;

Fig. 9 is a fragmentary transverse vertical section through one of the bins;

Figure 10 is a vertical section of the pressure cylinder and associated parts; and

Figures 11, 12 and 13 are detail sections of the clutches in various positions.

Reference to these views will now be made by use of like characters which are employed to designate corresponding parts throughout.

The scow comprises a hull 1 over the top of which is built a deck 2. In the deck is retained a longitudinal opening 3 at the

edges of which are disposed longitudinal walls 4 and transverse walls 5 extending downwardly to the bottom of the hull. The space defined by the walls is divided by a number of transverse partitions 6 which form a central bin 7 which is flanked on either side by similar bins 7^a and 7^b in succession.

In the lower end of each bin is provided a pair of section 8 hinged to the longitudinal walls 4 as clearly illustrated in Figure 9. These sections constitute the bottom of the barge and are controlled in their opening and closing by the mechanism constituting the subject matter of the invention.

Upon the deck are mounted upright bearings 9 in which are journaled a series of aligned shafts 10, 10^a and 10^b corresponding to the bins 7, 7^a and 7^b respectively. The sheaves on the shaft 10 are both indicated by the numeral 11 since they are simultaneous in function. The sheaves at the ends of the shaft 10^a are indicated by the numerals 12 and 12', and these carried by shaft 10^b are designated as 13 and 13'. The inner face of each sheave is formed with a collar 14 which serves as a spacer with respect to the adjacent bearing 9. The outer faces of the sheaves, with the exception of the extreme members 13', are formed with projections or teeth 11^a, 12^a, 12'^a and 13^a, corresponding to the sheaves of the same numerals, as illustrated in Figure 5. These members are 85 in the path of one another, and a pair of adjacent members may thus function as a clutch. It will be seen, particularly from Figure 7, that the lateral edges of these teeth are inclined as at 15 to provide a secure engagement.

The central shaft 10 carries a pinion 16 meshing with a vertical rack 17 which extends into the hold 18. The hold contains a pressure cylinder 19 which is entered by 95 the lower end of the rack, the latter being provided with a piston 20 acting in the cylinder. A fluid pressure pipe 21 extends from a suitable source to the lower end of the cylinder, and opposite the entrance of this pipe is provided a relief 22 of comparatively small diameter in reference to the inlet pipe. When fluid is admitted to the cylinder 19, the rack is lifted to actuate

the pinion 16. When the supply is cut off, the fluid within the cylinder escapes through the relief 22.

Each shaft 10, 10^a and 10^b carries a ratchet 23 engageable by a pawl pivoted to the deck 2.

Each sheave carries a transverse spindle 25 to which is secured the end of a cable 26. The cables secured to the sheaves on given 10 shaft, pass through the adjacent wall 4 and into the corresponding bin. A longitudinal rod 27 is passed through by the bins and carries guides 28 over which the cables are trained. To the remaining end of each 15 cable 26 is secured a pair of chains 29 attached to the inner edges of the corresponding hinged sections 8.

The operation of the device is as follows: When the scow is to be emptied, the pawl 20 adjacent the central shaft 10 is released from its ratchet, whereby the sections 8 of the central bin are opened downwardly by the weight of the load. The downward pull on the central cables 26 causes the 25 shaft 10 to turn until the sections 8 have reached their downward limit, at which instant the projections 11^a engage the projections 12^a. The relation of the teeth 11^a and 12^a, at the beginning and end of the 30 rotation of the shaft 10 is shown in Figures 11 and 12 respectively. When it is desired to empty one or both bins 7^a, according to a safe rate of discharge, the corresponding pawl 24 is released for one or 35 both bins, as the case may be. Considering only one of these bins, since the action is the same on either side, the shaft 10^a is brought into rotation in the manner already described until the corresponding sections 8 40 reach their downward limit and the projection 12^a engages the projection 13^a as shown in Figure 13. Finally, at the proper time in accordance with a safe rate of discharge, the pawl adjacent the shaft 10^b is released. 45 Obviously, this construction may be extended to any desired number of bins. To close the hinged sections after discharge of the bins, the rack 17 is set in operation by admission of pressure fluid into the cylinder 19. The piston and rack are raised, thereby turning the pinion 16 and shaft 10 50 in the reverse direction of that followed in the opening of the bins. The teeth or projections of adjacent shafts, having been brought into engagement by turning in the 55 direction for opening the sections 8, will act as positive clutch connections among the shafts in the reverse or closing direction. The shafts 10^a and 10^b will reverse simultaneously with the shaft 10, and all the doors 8 will close together. Obviously the sheaves 60 wind the cables 26 and raise the sections 8 to closed position as illustrated in Figure 9.

While a specific embodiment of the invention has been illustrated and described, it

is to be understood that various alterations in the details of construction may be made without departing from the spirit of the invention as indicated by the appended claims.

Having thus fully described the invention, what we claim as new and desire to protect by Letters Patent is:—

1. A dumping scow comprising a hull and a deck, partitions dividing said hull into a plurality of bins, hinged sections in said bins forming the bottom of the scow, a shaft journalled adjacent each bin and operatively connected to the sections in said bin, separate locking means for each shaft, and clutch connections among all said shafts. 70

2. A dumping scow comprising a hull and a deck, partitions dividing said hull into a plurality of bins, hinged sections in said bins forming the bottom of the scow, a shaft journalled adjacent each bin and operatively connected to the sections in said bin, ratchets carried by said shafts, and pawls mounted on said decks and adapted for engagement with said ratchets, and clutch connections among all said shafts. 80

3. A dumping scow comprising a hull and a deck, partitions dividing said hull into a plurality of bins, hinged sections in said bins forming the bottom of the scow, a shaft journalled adjacent each bin, sheaves mounted on said shafts and having flexible connections to the corresponding hinged sections, separate locking devices for said shafts, and clutch connections among all 90 said shafts. 95

4. A dumping scow comprising a hull and a deck, partitions dividing said hull into a plurality of bins, hinged sections in said bins forming the bottom of the scow, a shaft journalled adjacent each bin and operatively connected to the sections in said bin, ratchets carried by said shafts, pawls pivoted to said deck and adapted for engagement with said ratchets, and clutch 100 connections among all said shafts. 105

5. A dumping scow comprising a hull and a deck, partitions dividing said hull into a plurality of bins, hinged sections in said bins forming the bottom of the scow, a shaft journalled adjacent each bin, sheaves mounted on said shafts and having flexible connections to the corresponding hinged sections, separate locking devices for said shafts, teeth carried by said sheaves, the teeth of each sheave being adapted to engage the teeth of the sheaves on the adjacent shafts. 115

6. A dumping scow comprising a hull and a deck, partitions dividing said hull into a plurality of bins, hinged sections in said bins forming the bottom of the scow, a shaft journalled adjacent each bin and operatively connected to the sections in said bin, ratchets carried by said shafts, pawls 120

pivoted to said deck and adapted for engagement with said ratchets, teeth carried by said sheaves, the teeth of each sheave being adapted to engage the teeth of the 5 sheaves on the adjacent shafts.

7. A dumping scow comprising a hull and a deck, partitions dividing said hull into a plurality of bins, hinged sections in said bins forming the bottom of the scow, 10 a shaft journalled adjacent each bin and operatively connected to the sections in said bin, separate locking means for each shaft, clutch connections among all said shafts, a pinion carried by one of said shafts, and 15 a slideable rack meshing with said pinion.

8. A dumping scow comprising a hull and a deck, partitions dividing said hull into a plurality of bins, hinged sections in said bins forming the bottom of the scow, 20 a shaft journalled adjacent each bin and operatively connected to the sections in said bin, ratchets carried by said shafts, pawls pivoted to said deck and adapted for en-

gagement with said ratchets, clutch connections among all said shafts, a pinion carried 25 by one of said shafts, and a slideable rack meshing with said pinion.

9. A dumping scow comprising a hull and a deck, partitions dividing said hull into a plurality of bins, hinged sections in 30 said bins forming the bottom of the scow, a shaft journalled adjacent each bin and operatively connected to the sections in said bin, ratchets carried by said shafts, pawls pivoted to said deck and adapted for engagement with said ratchets, teeth carried 35 by said sheaves, the teeth of each sheave being adapted to engage the teeth of the sheaves on the adjacent shafts, a pinion carried by one of said shafts, and a slideable 40 rack meshing with said pinion.

In witness whereof we have hereunto set our hands.

GÉDÉON MAROTTE.
HORACE DUSSAULT.
